UNITED STATES PATENT OFFICE.

WINTHROP W. BENNER, OF AKRON, OHIO, ASSIGNOR TO FIRESTONE TIRE AND RUBBER COMPANY, OF AKRON, OHIO, A CORPORATION OF OHIO.

PLATING APPARATUS.

Application filed December 30, 1924. Serial No. 758,835.

To all whom it may concern:

Be it known that I, WINTHROP W. BENNER, a citizen of the United States, and a resident of Akron, county of Summit, State of Ohio, have invented certain new and useful Improvements in Plating Apparatus, of which the following is a specification.

This invention relates to devices for plating annular articles such as tire rims or the like and particularly to means for intermittently turning rims on their supports while being conveyed through a plating apparatus to insure a uniform plating of the rims.

Heretofore various devices have been employed in the art with more or less success for turning the rims while suspended in the plating bath and conducted therethrough. The present invention is directed to a greatly improved construction by which the mounting of devices within the tank controlled from the outside thereof is avoided, an apparatus embodying the invention being entirely automatic in its operation.

One object of the invention is to provide an electrically operated device for turning the rims and more particularly to provide magnetized members for engaging the rims to grip them and cause them to drag on the conveyor hooks on which they are suspended and to provide automatic means for demagnetizing the members to release the rims after the desired degree of turn has been effected.

The foregoing and other objects are obtained by the structure illustrated in the accompanying drawings and described below, it being understood that the invention is not limited to the specific construction shown and described.

Of the accompanying drawings:

Figure 1 is a longitudinal section through a portion of the plating system and illustrating a device constructed according to the invention mounted for operation therein;

Figure 2 is a transverse section through a portion of the system;

Figure 3 diagrammatically illustrates the electrical connections; and

Figure 4 is a detail illustrating the manner of mounting the magnetic turn-over device.

Figure 5 is an enlarged section on the line 5—5 of Figure 1.

Referring to the drawings, 10 is a suitable tank containing an electrolyte 11, anodes 12, 12 supported on conductor rails 13, 13 so as to be suspended in the electrolyte 11. The articles to be plated, here represented as rims 14, 14 are suspended in the solution on hooks 15, 15 arranged to be carried by a moving conveyor chain 16, the rims being adapted to act as cathodes as by connecting hooks 15 by brushes or the like to a suitable conductor rail (not shown).

Arranged on brackets 17, 17 supported over tank 10 are electromagnets 18, 18 suspended on insulated bushings 19 pivotally mounted on pintles 20, 20 secured in brackets 17 so as to overlie the path of the rims 14. The poles 21, 21 of the magnets are provided with hinged fingers 22, 22 extending into the path of the rims through the tank and adapted to be engaged thereby.

For normally keeping the fingers 21 magnetized so as to grip rims coming into engagement therewith the magnets 18 are supplied with electricity through a switch 23 as indicated in Figure 3 normally kept closed by a spring 24. While the magnets are energized through the electrical connections described, they will operate to grip each rim as it comes in contact with the fingers 21, and while each magnet is effective it will operate as a drag upon the rim, and the continued movement of the conveyor will cause the rim to be shifted upon the hook without, however, destroying the electrical contact between the rim and the hook so that the plating action is not interrupted. After the conveyor has traveled for a distance sufficient to cause the rim to be rotated, it is necessary to release the magnet which may be accomplished by the operation of the switch 23.

One means of doing this is by the mechanism which will now be described. Connected to the switch 23 by a link 25 is a lever 26 pivoted at 27 so as to extend into the path of chain 16 and to be engaged by spaced members thereon, such, for example, as transverse rods 29 forming part of the conveyor mechanism, the rods 29 on which the hooks 15 are suspended being adapted to engage the lever 26 in succession to open switch 23 against the action

of spring 24 and thus demagnetize the fingers 22 to release the rim and fall back into a position for engagement with a succeeding rim.

5. The operation of the device, which will be readily understood from the foregoing, may be briefly described as follows:

The rims 14 are continuously advanced through the tank 10 to be plated. Any desired number of the magnetic devices are spaced along the tank and as the rims contact with the normally magnetized fingers 22, they are gripped and held. Due to the travel of the conveyor, the rims are dragged 10 so as to rotate to new positions on the hooks, this dragging and rotating action continuing at each device until the rods 29 engage the levers 26 whereupon switches 23 are opened and the fingers 22 release the rims 15 to continue their travel on the hooks.

It will be noted that in the form of the invention shown the rims are elevated at the turning station by a rise in the conveyor. This is preferred so as to admit 20 of easy mounting of the magnetic devices in the system but is not essential to the operation of the devices and the devices may be adapted to conveyor systems in which the rims are not elevated at the turn-over stations.

Modifications of the invention may be resorted to without departing from the spirit thereof or the scope of the appended claims. It will be noted that the turn-over 25 device of the present invention operates without lifting the rims from the hooks. Accordingly, the plating action on the rim will be effective during the turning action. This provides for a highly efficient, continuous plating process.

What is claimed is:

1. An apparatus for electroplating annular objects, a continuously moving conveyor, hooks upon the conveyor from which the articles are suspended in an electroplating bath, and a device for engaging the upper part of an object and holding it for a period sufficient to cause it to drag over the hook to a new position.

50. 2. An apparatus for electroplating rims comprising a continuously moving conveyor, a hook upon the conveyor from which a rim is suspended in an electroplating bath, and a device for engaging a rim and causing it to drag over the hook to a new position upon the hook without destroying the electrical contact between the hook and the rim.

60. 3. An apparatus for electroplating rims comprising a continuously moving conveyor, a hook upon the conveyor from which a rim is suspended in an electroplating bath, a device for engaging a rim and causing it to drag over the hook to a new position upon the hook without destroying the

electrical contact between the hook and the rim, and means for causing the device to release the rim.

4. An apparatus for electroplating rims comprising a continuously moving conveyor, a hook upon the conveyor from which a rim is suspended, and means operating for an interval of travel of the conveyor for dragging the rim over the hook without destroying the electrical contact between the hook and the rim. 70

5. Apparatus for treating annular articles comprising a conveyor on which the articles are carried, and means for gripping the articles to turn the articles on the conveyor. 80

6. Apparatus for treating annular articles comprising a conveyor on which the articles are carried, and magnetic means for gripping the articles to turn the articles on the conveyor. 85

7. Apparatus for treating annular articles comprising a conveyor on which the articles are carried, and electromagnetic means for gripping the articles to turn the articles on the conveyor, said means being automatically disengaged from the articles after the desired turning is effected. 90

8. Apparatus for treating annular articles comprising a conveyor on which the articles are carried, electromagnetic members adapted to grip the articles to effect a turning thereof on the conveyor, and means for demagnetizing the members after the desired turning is effected. 95

9. Apparatus for treating annular articles comprising a conveyor on which the articles are carried, electromagnetic members adapted to grip the articles to effect a turning thereof on the conveyor, and means operable by the conveyor for demagnetizing the members after the desired turning is effected. 100

10. Apparatus for plating annular articles comprising a tank for an electrolyte, a conveyor passing over the tank, means for suspending the articles on the conveyor so as to conduct them through the electrolyte, and electromagnetic gripping means for engaging the articles and holding the articles so as to rotate them to new positions on the suspending means. 110

11. Apparatus for plating annular articles comprising a tank for an electrolyte, a conveyor passing over the tank, means for suspending the articles on the conveyor so as to conduct them through the electrolyte, and electromagnetic gripping means for engaging the articles and holding the articles so as to rotate them to new positions on the suspending means, said electromagnetic means being controlled by the conveyor so as to automatically release the articles after the desired turning thereof has been effected. 120

12. A device of the character described 125

comprising means for conveying annular articles, and an electromagnet, including a pole projecting into the path of the articles to grip and hold the same to effect a rotation thereof on the conveying means.

13. A device of the character described comprising means for conveying annular articles, and an electromagnet, including a pole projecting into the path of the articles to grip and hold the same to effect a rotation thereof on the conveying means, said pole being adapted to ride over the articles when demagnetized.

14. A device of the character described comprising means for conveying annular articles, and an electromagnet, including a pole projecting into the path of the articles to grip and hold the same to effect a rotation thereof on the conveying means, said pole being pivoted so as to be suspended in the path of the article.

15. A device of the character described comprising means for conveying annular articles, and an electromagnet, including a pole projecting into the path of the articles to grip and hold the same to effect a rotation thereof on the conveying means, said electromagnet being normally energized but adapted to be automatically deenergized to release the articles.

16. Apparatus of the class described said apparatus comprising a conveyor for carrying articles, electromagnetic means normally energized to grip articles carried on the conveyor, and means for deenergizing the electromagnetic means to release the articles.

17. Apparatus of the class described said apparatus comprising a conveyor for carrying articles, electromagnetic means normally energized to grip articles carried on the conveyor, and means for deenergizing the electromagnetic means to release the articles, said means including a switch controlled by the conveyor.

18. Apparatus of the class described said

apparatus comprising a conveyor for carrying articles, electromagnetic means normally energized to grip articles carried on the conveyor, and means for deenergizing the electromagnetic means to release the articles, 50 said means including a switch, means normally closing the switch, and means on the conveyor for opening the switch.

19. Apparatus of the class described said apparatus comprising a conveyor for carrying articles, electromagnetic means normally energized to grip articles carried on the conveyor, and means for deenergizing the electromagnetic means to release the articles, 55 said means including a switch, yielding means normally closing the switch, and means on the conveyor for opening the switch against the action of the yielding means.

20. Apparatus for plating rims including a plating tank, a conveyor for carrying rims through the tank, and means for gripping the rims in succession to reposition them on the conveyor.

21. Apparatus for plating rims including a plating tank, a conveyor for carrying rims through the tank, and means for gripping the rims in succession to reposition them on the conveyor and then releasing the rims 70 for travel with the conveyor.

22. Apparatus for plating rims including a plating tank, a conveyor for carrying rims through the tank, and means for gripping the rims in succession whereby movement of the conveyor relative to the rim 75 will effect a repositioning of the rim thereon.

23. Apparatus for plating rims including a plating tank, a conveyor for carrying rims through the tank, and means for gripping the rims in succession whereby movement 80 of the conveyor relative to the rim will effect a repositioning of the rim thereon, said means being adapted to subsequently release the rim.

WINTHROP W. BENNER.
